UNITED STATES PATENT OFFICE.

GUY J. EVANS, OF BUFFALO, NEW YORK.

ADDRESSING-MACHINE.

1,253,361.

Specification of Letters Patent. Patented Jan. 15, 1918.

Application filed April 23, 1915. Serial No. 23,377.

To all whom it may concern:

Be it known that I, GUY J. EVANS, a citizen of the United States, residing at Buffalo, in the county of Erie and State of New York, have invented new and useful Improvements in Addressing-Machines, of which the following is a specification.

This invention relates to an addressing machine which is more particularly designed for printing addresses on envelopes, letter heads and the like by pressing ink through a stencil while the latter is applied to the article to be addressed.

It is the object of this invention to produce a machine of this character whereby such addressing may be effected conveniently and expeditiously, which is simple and compact in construction and efficient in operation, and which can be produced at comparatively low cost.

In the accompanying drawings: Figure 1 is a top plan view of an addressing machine embodying my invention. Fig. 2 is an end elevation of the same. Fig. 3 is a bottom plan view thereof. Fig. 4 is a vertical transverse section of the machine taken on line 4—4, Fig. 1. Fig. 5 is a vertical longitudinal section taken on the correspondingly numbered line in Fig. 1. Fig. 6 is a vertical section taken on line 6—6, Fig. 4. Figs. 7 and 8 are fragmentary vertical sections, on an enlarged scale, taken on the correspondingly numbered lines in Fig. 5.

Similar characters of reference indicate corresponding parts throughout the several views.

In its general organization this machine is provided with means for supporting the article to be addressed at the printing position, means for successively feeding stencils from a supply stack to the printing position over the article to be addressed, and means for producing an impression of the stencil on such articles, the impression devices being operatively associated with the stencil feeding mechanism, so that the latter is automatically actuated upon moving the impression device.

The frame of the machine which supports the working parts may be variously constructed but as shown in the drawings the same preferably comprises a horizontal table 1 arranged with its length in a direction transversely of the machine and provided at its front and rear ends with feet

or lugs 2, 3 whereby the same may be supported upon a table or elsewhere. Upon the front part of this table is arranged a horizontal platen 4 upon which the article to be addressed, such as an envelop or letter head, is supported at the printing position while the impression of a stencil is produced thereon. When envelopes or the like are being addressed it is preferable to register the same in printing position by engaging the upper edge of the envelop with a top gage 5 arranged on the table 1 immediately adjacent to the rear edge of the platen, as shown in Figs. 2 and 4, and also engaging the left hand edge of the envelop with a side gage 6 which is mounted on the adjacent stationary part of the machine. The upper gage is preferably fixed but the side gage may be adjustable in the direction of the length of the envelop by means of an adjusting screw 7 engaging a bracket 10 of a main frame, and passing through a longitudinal slot 9 formed in an arm 8 on the side gage, as shown in Fig. 1. Upon loosening the screw 7 and shifting the side gage lengthwise in one direction or the other the latter may be adjusted to suit the envelopes which are being addressed or to permit of placing this address on any particular part of the envelop as desired.

When addressing letter sheets or the like it is preferable to engage the lower edge of such sheets with a bottom gage 11 and the left hand edge thereof with the side gage 6. This bottom gage is also preferably capable of adjustment transversely of the machine and this is preferably accomplished by securing this gage to a transverse arm 12 which is secured to the upper side of the platen so as to be capable of transverse adjustment thereon by means of a screw 13 passing through this platen and a transverse slot 14 in said adjusting arm 12, as shown in Fig. 1.

The stencils whereby these addresses are produced may be variously constructed but they preferably consist of thin sheets 17 of strong material in which the address perforations are produced by any suitable means and a frame 16 of thicker material upon which the edge of each stencil sheet is mounted, these stencils being preferably of rectangular form, as shown in the drawings. Although these stencils may be placed over the article to be addressed at the printing position either manually or automatically

it is preferable to employ for this purpose means whereby the same are fed successively by automatic means from a stack to the printing position. For this purpose a stack 5 of such stencils is arranged in a magazine 15 which is mounted on the upper side of an arm 18 arranged lengthwise of the machine and projecting laterally from the right hand side of the table. This magazine is 10 open at the top to permit of introducing the pile or stack of stencils downwardly into the same and also provided at its opposite ends with vertical slots 19 for convenience in manipulating the stencils and also enabling 15 the operator to observe when the supply of the same is about exhausted and needs replenishing. The lower end of the magazine is open so that the stencils can be fed horizontally one at a time from the under- 20 side of the stack in the magazine. This feeding-off mechanism is so organized that whenever a stencil is fed away from the bottom of the stack the latter drops by gravity and brings the next following stencil to the 25 feeding-off position. To facilitate this dropping of the stack a weight 20 is preferably placed on the upper side of this stack, as shown in Figs. 1, 2, 4 and 5. In the preferred construction the lower end of the 30 magazine is arranged with its opposite longitudinal edges adjacent to the upper side of two longitudinal guide rails 21 which are also mounted on the supporting arm 18 and operate to direct the stencils from the under- 35 side of the magazine to the printing position and then discharge the same at a point on the opposite side of the table. These rails are preferably constructed in the form of channels which have their grooved sides 40 facing each other, the distance between the channels of these rails being equal to the width of a stencil. Immediately below the magazine the upper flanges of the rails are cut away, as shown at 22 in Fig. 7, so that 45 the lower end of the magazine can open directly into the channels of these rails and permit the lowermost stencil of the pile in the magazine to rest upon the lower flanges 23 of the rails while the next following up- 50 per stencil is arranged above these channels and out of the path of the devices which operate to feed the lowermost stencil from the bottom of the pile. This feeding-off device preferably comprises a feeding plate 24 55 which is equal in thickness to the stencil frames and is guided at its opposite longitudinal edges in the channels of the rails. While this feeding plate is shifted from underneath the magazine the weight of the 60 stack of stencils in the case causes the lowermost one to be pressed against the lower flanges of the rails. Upon now moving the feeding plate forwardly the same engages its front edge with the rear edge of the 65 lowermost stencil and pushes the same for-

wardly from underneath the pile, the extent of this forward movement of this feeding plate being so determined that the rear edge of the stencil which has just been fed off clears the bottom of the pile at the end of the forward stroke of this plate. During its return stroke the feeding plate again clears the bottom of the pile so as to permit the next following lowermost stencil of the pile to be depressed until it rests on the lower flanges of the rails and is arranged in the path of the feeding plate preparatory to being fed away from the pile during the next following forward stroke of the plate. As each stencil moves forwardly in the rails the same by engaging its front edge with the rear edge of the stencil immediately in front of the same, causes the latter to be also advanced and shifted not only to the printing position but also to be discharged from the front ends of the rails which are located at the left hand side of the table where the stencils after being used at the printing position are automatically stacked or gathered in a pile. For this purpose a receiving magazine 25 is provided which is mounted on the frame at the left hand side of the table and which has an open top arranged adjacent to the delivery ends of the rails so that the stencils are discharged successively from the rails into this receiving magazine. The bottom of the latter is closed so as to support this stack of used stencils. The corners of the receiving magazine are preferably open, as shown at 26 for convenience in removing the gathered stack of used stencils therein and stowing the same away for further use. The underside of the receiving magazine is preferably flush with the undersides of the supporting legs 2, 3 so that the addressing machine may be placed on top of a table or similar support when it is desired to use it.

As each stencil is arranged over an envelop or other article at the printing position an impression of the same is produced on this article by means of a printing device which preferably comprises a flexible or elastic printing or impression roller 27 which is provided on its periphery with a coating of ink so that upon pressing this roller downwardly with its inked surface upon the perforated sheet of a stencil the ink of this impression roller will be pressed through this stencil and upon the article beneath the same so as to leave an address thereon. This impression or printing roller may be constructed of rubber or composition in the usual and well known manner and is mounted on a horizontal shaft 28 which is journaled lengthwise of the machine in a carriage 29 movable back and forth in a direction transversely of the machine from a position over the stencil to a position in rear thereof. While in its rearward or inoperative position the impression roller is sup- 130

ported upon an ink supply plate 30 which is mounted on the upper rear part of the table but separated therefrom by an intervening space and over which the printing or impression roller is moved while the same is not in engagement with the stencil for the purpose of aiding in distributing the ink uniformly over the entire periphery of the impression roller. The backward and forward movement and also the pressure for causing the same to produce an impression on the article to be addressed are effected by hand for which purpose the carriage is provided on its front side with a forwardly projecting handle 31 which is grasped by the operator. During its forward and backward movement the printing carriage is guided by means of a yoke which comprises a horizontal top bar 32 secured to a lug 33 projecting rearwardly from the central part of the carriage, and two vertical arms 34, 35 projecting downwardly from the top bar, one of said arms engaging with the side edge of the inking plate and provided at its lower end with an inwardly projecting lug 36 which engages with the underside of this plate while the other arm engages with the opposite side of the inking plate and the adjacent side of the table and is provided at its lower end with an inwardly projecting lug 37 arranged below the table, as shown in Fig. 6. As the printing carriage is moved backward and forward the yoke guides the same relatively to the table and inking plate and while the printing carriage is in its foremost position with the impression roller over the stencil this yoke also forms a fulcrum about which the carriage and the parts mounted thereon may turn in a vertical plane while the handle 31 is depressed for producing an impression by means of the printing roller through the stencil on the article to be addressed.

In order to prevent an excessive pressure from being applied to the printing or impression roller the front part of the frame is provided with a stop device which preferably consists of an upright post 38 secured to the upper front part of the table, as shown in Figs. 1, 2 and 4. Upon depressing the handle of the carriage while the impression roller is over the stencil this handle engages the upper end of the stop post 38 and limits the depression thereof so that all of the impressions of the stencils on the successive articles which are being addressed will be uniform.

After the impression roller has been pressed downwardly against a stencil the carriage supporting this roller is again moved backwardly into its rearmost position. The forward and backward movement of the carriage may be limited in various ways, for instance, by means of front and rear stops 39, 40 which are secured

to the inking plate in position to be engaged by the arms of the guide yoke at the end of the forward and backward stroke of the carriage.

For the purpose of replenishing the ink supply on the surface of the impression roller from time to time the upper surface of this roller is engaged by a removable ink supply roller 41 which latter may be supplied with ink from any suitable source and then this ink supply roller is mounted on the carriage so that its periphery engages with the ink delivery or impression roller for supplying the latter with ink. In order to enable this ink supply roller to be conveniently detached from the carriage and reassembled therewith for the purpose of replenishing the ink supply, this roller is mounted on a shaft 42 the opposite ends of which are adapted to engage with upwardly opening bearing notches or slots 43 in the end walls of the printing carriage and are also journaled in the opposite arms 44 of a fork which is adapted to rest on the adjacent rear part of the carriage and provided with a rearwardly projecting handle 45 for manipulating the ink supply roller. Normally the latter rests by gravity on the impression roller and is turned by the latter so that the ink is not only transferred continuously from the supply roller to the impression roller but the same is also distributed more or less which distribution is further continued as the impression roller is passed back and forth over the inking plate.

By making the ink supply roller detachable in the manner shown and described the same can be quickly removed from the carriage and re-applied thereto for maintaining a substantially uniform supply of ink and without interrupting the operation of the machine.

Means are provided whereby the forward and backward movement of the printing carriage is utilized to automatically move the stencil feeding plate backwardly and forwardly and thereby not only avoid the necessity of separately operating the stencil feeding mechanism but also causing these parts to operate in harmony with each other and expediting the operation of addressing envelopes or the like.

The preferred means for this purpose as shown in the drawings comprises a horizontally swinging lever 46 which is pivoted on a bracket 47 projecting laterally toward the right from the rear part of the table and connected at its rear end by means of a link 48 with the lower lug 37 of the yoke while its front end is connected by means of a link 49 with the underside of the stencil feeding plate, the pivotal connection between the last mentioned link of the stencil feeding plate extending through a longitudinal slot 50 of the supporting arm, as shown

in Figs. 1, 2, 3, 4 and 5. Due to this mechanism the feeding plate is caused to move forward and feed a stencil from the bottom of the stack while the printing carriage is 5 moving backwardly from the printing position to the inking plate, and while the printing carriage is moving forwardly from the inking plate to the printing position the feeding plate is retracted into its rearmost 10 position preparatory to feeding the next stencil from the stack. The feeding of the stencils successively from the underside of the pile to the printing position and from the latter to the receiving magazine is 15 therefore effected automatically and in proper time with the operation of the printing device so that the operator need pay no attention to the stencils excepting to see that the supply is replenished from time to time, 20 thereby enabling the operator to pay practically his entire attention to the placing of the envelopes or letter sheets in the proper position on the platen to receive the impression of the stencil, and thereby not only insure 25 work of uniform quality but also increasing the capacity of the machine accordingly.

I claim as my invention:

1. An addressing machine comprising a 30 table, a platen adapted to support an article to be addressed at the printing position, means for feeding stencils to said platen, an inking plate supported on said table adjacent to said platen but spaced therefrom, 35 an ink impression roller movable over said inking plate and to and from said printing position, and adapted to press ink through the stencil on an article; a carriage supporting said roller and having a handle on its 40 front side and a yoke connected with the rear side of said carriage and having a part 45 slidably between said table and inking plate.

2. An addressing machine comprising a table, a platen adapted to support an article 45 to be addressed at the printing position, an inking plate supported on said table adjacent to said platen but separated therefrom by an intervening space, an impression roller

movable over said inking plate and to and from said printing position, a carriage 50 supporting said roller and having a handle on its front side and a lug on its rear side, and a guide yoke having a top bar arranged above the inking plate and connected with said lug, and two arms projecting from said 55 bar downwardly along opposite edges of said plate and table and one of said arms being provided with a lug projecting underneath said plate and the other arm being provided with a lug projecting underneath 60 said table.

3. An addressing machine comprising an impression roller adapted to press ink on its surface through a stencil on the article to be addressed, a carriage supporting said roller and provided with upwardly opening bearing notches on its opposite sides, an ink supply roller engaging said impression roller, a shaft on which said ink supply roller is mounted and which is journaled at 70 its opposite ends in said bearing notches, and a fork on which opposite ends of said shafts are journaled and which is provided with a handle.

4. An addressing machine comprising a 75 platen adapted to support an article to be addressed at the printing position, a magazine adapted to support a stack of stencils, means for guiding the stencils from said magazine to said printing position, a feed 80 plate movable lengthwise of said guide and past the underside of the magazine for feeding the stencils successively from the underside of the stack along the guideway to said printing position, an impression roller engaging the stencils at the printing position, a carriage supporting said roller and movable toward and from the printing position, and actuating means connecting said carriage and feed plate and operating to cause 85 the feed plate to move forwardly while the carriage moves rearwardly, and vice versa, and comprising a rock lever and links connecting opposite ends of said lever with said feed plate and carriage, respectively.

GUY J. EVANS.
